MOUNT FOR TELESCOPIC SIGHTS

Ernest L. Meisel, Baltimore, Md.

Application June 26, 1940, Serial No. 342,583

2 Claims. (Cl. 33—50)

The present invention relates to means for mounting a telescope on a rifle, and more particularly to a mount that can be easily secured to and removed from the rifle and in which the windage adjustment is not affected when the mount is removed. While the description of the invention is directed primarily to a construction for hunting "scopes," it is of course obvious that it can be used for target "scopes."

It is well known that there has been an increased demand to employ telescope sights in lieu of the well known iron sights. However, the problem of mounting the "scope" on the rifle has resulted in heavy, clumsy and otherwise objectionable mounts. Manifestly, the employment of a low mounted "scope" will afford the best results since such a mount is more durable, less cumbersome and top heavy and permits the firm cheeking of the stock. Here again the structure of the mount has been cumbersome to provide the necessarily rugged windage adjustment for the "scope."

The larger and the heavier the hunting "scope" and the higher it is mounted, the more opportunity there is that it will be knocked out of alignment, and these high mounted "scopes" require a much heavier and stronger mount than do the mounts which are placed low on the rifle barrel. A "scope" mount rarely improves the general appearance of the rifle, but the higher the "scope" is positioned, the more unsightly the appearance of the gun becomes. Another important reason why the high "scope" mounts are not particularly desirable is that a rifle thus equipped, due to increased parallax, does not shoot especially accurately, and as a matter of fact better results can be achieved with the iron sights than with such a "scope."

We may classify the hunting "scope mounts" that are used at the present time into two classes—first, the bridge type, and second, the side bracket type. The merits of each of the above mentioned mounts are well known and it is sufficient to say that heretofore in the bridge type mounts, it has not been possible to position the "scope" quite as low as can be done with the side bracket type.

These prior mounts I find possess certain undesirable characteristics. For example, the bases that are used are especially made for the job and detract greatly from the appearance of the gun. In addition, it is usually necessary when the "scope" is removed to disturb the windage adjustment, and as a consequence necessitates "shooting in" the rifle to obtain the same ad-

justment when the "scope" is replaced. Also, some of the mounts have been of such construction that they are subject to serious damage being removed by unskilled hands, and a damaged mount as a general proposition makes the use of "scope" sights impractical.

An object of the present invention is to overcome the above and other disadvantageous features that now confront the art.

10 Another object of my invention is to provide a mount for a rifle telescopic sight which may be readily removed and replaced on the rifle without affecting the windage setting of the sight.

Another object of my invention is to provide a 15 "scope" mount that is simple in construction and operation and which can be cheaply and easily manufactured.

Still a further object of my invention is to 20 provide a mount for "scope" sights which presents a pleasing appearance and the exposed surfaces of which are free from any projections or protuberances that often prove undesirable in the hunting fields.

25 Yet another object of my invention is to provide a bridge type hunting "scope" that is mounted low on the barrel of the rifle but which is of sufficient height to permit bolt action rifles to be easily operated.

And a further object of my invention is to 30 provide a mount for hunting "scopes" that will effectively withstand the recoil shock of the rifle.

Still another object of my invention is to 35 provide a "scope" mount having incorporated therein a windage adjustment that can only be changed by the user of the gun.

To accomplish the foregoing and other objects, my invention in general comprises a front and rear clamp for a "scope" sight. These clamps 40 coat with mounting plates detachably connected to and bridging the receiver of the rifle. The clamps are dovetailed to the mounting plates in such a manner that they will only have motion in one plane.

A windage adjustment is associated with the 45 rear clamp and adjustment, and once having been made by the operator of the gun, cannot be changed by removal of the "scope" and mount from the gun.

In the drawings in which like numerals indicate the same or similar parts:

Figure 1 is a view in side elevation showing my "scope" mount bridging the receiver of a bolt action rifle.

Figure 2 is a view in perspective of the rear 50 "scope" clamp.

Figure 3 is a view in perspective of the rear attaching clamp illustrating the windage adjustment.

Figure 4 is a view in perspective of the front "scope" clamp.

Figure 5 is a view in perspective of the front attaching clamp.

Figure 6 is a longitudinal vertical sectional view of the rear "scope" clamp.

Figure 7 is a longitudinal vertical sectional view of the front "scope" clamp.

Figure 8 is a sectional view taken along the line 8-8 of Figure 6 looking in the direction of the arrows.

Figure 14 is a view in side elevation of the front mount used with the rear mount shown in Figure 13.

Figure 15 is a sectional view taken along the line 15-15 of Figure 13 looking in the direction of the arrows.

Figure 16 is a sectional view taken along the line 16-16 of Figure 13 looking in the direction of the arrows.

Figure 17 is a sectional view taken along the line 17-17 of Figure 13 looking in the direction of the arrows.

Figure 18 is a sectional view taken along the line 18-18 of Figure 14 looking in the direction of the arrows.

Figure 19 is a sectional view taken along the line 19-19 of Figure 18 looking in the direction of the arrows.

In the drawings there is shown a rifle 1 of conventional construction having removably secured thereon a telescope 2. While the telescope 2 is the hunting type "scope," it is obvious that other kinds may be used. Mounted adjacent the receiver of the rifle are front and rear mounting blocks 3 and 4. As shown in Figure 9, the block 4 is of dovetail shape and is attached to the receiver ring by a screw 5, the head of which is counter-sunk as clearly illustrated. The mounting block 3 is of similar shape and is attached to the rifle barrel.

A forward base member 7 having a longitudinal dovetail groove 8 is adapted to slide over the mount 3. The upper face of the base is reduced at its forward end to form an extension 9 provided with a threaded aperture 10. The upper surface of the base is formed with an arcuate tongue 11 having an inclined edge 12 and a rectangular edge 13. The arcuate tongue 11 is concentric with the aperture 10.

A clamp 14 for the front end of the telescope is provided and it has a circular bore 15 that is split off center as shown at 16 in Figure 10. When the "scope" is positioned within the bore it is fixed thereto by counter-sunk tightening screws 17 provided in the clamp 14. The lower wall of the clamp is formed with a lateral arcuate

groove 18, the sides 19 and 20 of which coincide with edges 12 and 13 of the tongue 11 when the clamp is positioned on the base 7. The forward end of the clamp 14 has a counter-bored aperture 21 that is adapted to be disposed over the threaded aperture 10 formed in the extension 9 of the base 7. A shouldered pivot screw 22 is positioned in the apertures 21 and 10 for mounting the clamp 14 for pivotal movement on the base 7.

A rear base 23 provided with a longitudinal dovetail groove 24 in its undersurface is adapted to slide over the mounting block 4. The upper face of the base 23 is formed with a lateral dovetailed tongue 25, the angular edges of which are arcuate, and when the bases 7 and 23 are positioned on the rifle the angular edges are also concentric with the aperture 10.

The base 23 is also cutaway at its rear portion, as shown at 26 to provide horizontal lugs 27. Windage adjustment screws 28 extend through threaded apertures 29 in the lugs and are provided on their outer extremities with winged lock nuts 30.

The rear portion of the "scope" 2 is held in a clamp 31 having a central bore 32, and it will be seen that the clamp is split longitudinally along its lower face as at 33. The lower face of the clamp is formed with a lateral dovetail groove 34 with inclined faces 35 which engage the tongue 25 when the clamp is disposed upon the base 23. As best shown in Figures 2 and 8, the clamp 31 carries vertical lugs 36 at its rear end which when the clamp is disposed upon the base extend into the cutaway portion 26 between the windage adjustment screws 28. As a consequence, the proper windage adjustment can be effected by manipulation of the screws with respect to the lug 36 to move the scope about the pivot screw 22.

The attachment of the "scope" 2 and the clamp 31 is made by the adjustment of counter-sunk screws 37 provided along the lower edge of the clamp on either side of the dovetail groove 34.

The bases 7 and 23 are attached to the mounting blocks 3 and 4, respectively, as shown specifically in Figure 9. As the attachment is similar for both the front and rear mounts only that for the rear mount will be described. The base 7, adjacent the upper surface of the tongue 25 is cutaway as indicated by the numeral 40 and a sliding block 41 is disposed in the cutaway portion. The block 41 is provided with a flat 42 flush with the upper face of the tongue. The inner face of the block is concave as shown at 43 and is adapted to fit into a print 44 formed in the mounting block 4. A bolt 45 extends from the opposite side of the base 23 through bore 46 and its end threadedly engages the sliding block 41, as clearly shown in Figure 9. Consequently by tightening the bolt 45 the block 41 will be moved into engagement with the print 44, thus securing the base 23 thereto. Incidentally, it will be seen that the head of the bolt 45 is countersunk whereby the base will present no rough surfaces.

The removal of the scope and its attaching clamps and bases from the rifle and their subsequent replacement is relatively simple and constitutes a considerable improvement over the mounts which have heretofore been employed. As pointed out before one great disadvantage of these prior devices has been that when the telescope has been removed from the rifle it affects the windage adjustment which means of

course that the "scope" must be sighted in again when it is replaced on the gun. However, with my mounts the operator of the rifle does not have to bother in any way the windage adjustment when the "scope" is taken off. The bases 7 and 23 are removed simply by loosening the bolt 45 which frees the base from its respective mount on the gun and the bases, clamps and "scope" are thus free to be removed from the rifle in a fixed unit. This removal in no way disturbs the windage adjustment and the advantages thereof are believed readily apparent. The replacement of the "scope" is also a very simple matter since it merely means that the bases are slid onto the mounting blocks and the bolts 45 are drawn up to move the concave face 43 into engagement with the print 44 of each mount block.

Another desirable characteristic of my invention is that the mounts are very sturdy in construction and are so arranged that the "scope" is situated rather low on the rifle but is still high enough to permit the device to be used with a bolt action rifle. Also it will be seen that all of the securing devices such as bolts and screws are counter-sunk thus providing mounts which present a smooth outer surface and thereby obviating the danger of the mounts becoming entangled or caught by foliage, brush, or the like.

In Figures 13 to 19 inclusive I have shown a slightly modified form of my inventive concept. In this particular embodiment it will be seen that I provide a front base member 60 having a longitudinal dovetail groove 61 which slides over the mount 3. The upper face of the base is reduced at its forward end to form an extension 62 provided with a threaded aperture 63. The upper face of the base is also formed with a lateral dovetailed tongue 64, the angular edges of which are arcuate. These edges are also concentric with the aperture 63.

I provide a clamp 65 for the front end of the "scope" and it has a circular bore 66 which is split longitudinally as shown at 67. To attach the "scope" to the clamp it will be seen that one of the sides of the clamp is provided with bosses 68 into each of which is threaded a screw 69. The lower wall of the clamp 65 is provided with a lateral arcuate groove 70, the groove having an inclined edge 71 and a rectangular edge 72. It will be seen that the edge 71 coincides with one angular edge of the tongue 64 and to assure a correct fit between the clamp and the base, a gib 73 is positioned between the wall 72 and the other inclined face of the tongue 64. To adjust the gib 73 for proper sliding engagement between the clamp and the base, it will be seen that vertical threaded apertures 74 are provided in the base. Screws 75 are threaded in the aperture 74 and the upper ends of the screws bear against the lower face of the gib, and by tightening these screws the gib will be moved into a tighter fit with the tongue 64. A centering pin 76 is adapted to extend through an aperture 77 in the gib and fits in sockets 78 formed in the base 60.

The clamp 65 is pivotally attached to the base 60 in a similar manner to that shown in Figure 7 by the shouldered screw 22 being threaded into the aperture 63. The base 60 is attached to its mounting block 3 by securing device 89 which is similar in construction and operation to that previously described in connection with the forms shown in Figure 1.

A base 85 having a dovetail groove 86 in its

lower face slides over the rear mount block 4. The upper face of the base 85 is cutaway to form a lateral tongue 87 having an inclined arcuate edge 88 and a vertical arcuate edge 89. The edges 88 and 89 are concentric with the aperture 63 provided in the tongue 62.

The rear portion of the base 85 is cutaway to form lugs 90 and windage adjustment screws 91 extend through threaded apertures in each lug. Winged lock nuts 92 are threaded onto the outer ends of the screws 91.

A clamp 94 for the rearward end of the "scope" having a bore 95 is split as shown at 96. When the "scope" is disposed within the bore 95 it is secured therein by means of screws 97 which are threaded into apertures 98 formed in bosses 99.

In Figure 13 it will be seen that the lower face of the clamp 94 is provided with a lateral dovetail groove 100 that is wider than the tongue 87. When the clamp 94 is disposed upon the base 85, it will be noted that angular face 88 of the base coincides with one angular face of the dovetail groove 100, and a gib 101 having a vertical wall 102 is positioned between the vertical wall 89 of the tongue and the opposite angular wall of the groove 100. The base is provided with vertical apertures into which are positioned screws 103, the upper ends of which threadedly engage apertures formed in the gib 101. It is believed readily apparent that when the screw 103 is tightened the gib 101 will move downwardly thus affording a tight sliding fit between the groove 100 and the tongue 87. Moreover, by employing these gibs greater tolerances may be permitted than in the mounts illustrated in Figures 1 to 12, thereby greatly reducing the cost of manufacture.

The rear portion of the clamp 94 is formed with a downwardly extending member 104 which projects into the cutaway portion of the base 85 between the lugs 90. Consequently, by rotation of the screws 91 the proper windage adjustment of the "scope" can be effected.

The base 85 is removably attached to the mount block 4 by a securing device 105 which is similar to the member 88 shown in Figure 14 with reference to the front "scope" mount.

This particular embodiment affords a very effective "scope" mount and with the use of the gibs 73 and 101 provided in the front and rear "scope" mounts, respectively, there can be no binding between the base and the "scope" clamp. The mounts are removed from and replaced on the rifle in practically the same manner as those disclosed in connection with Figure 1.

From the foregoing description it will be appreciated that I have provided a mount for "scope" sights for a rifle that is relatively simple in construction and operation and which can be easily and cheaply manufactured. Furthermore, with my mounts the "scope" and its associated parts can be removed from the rifle or replaced on the rifle without disturbing the windage adjustment, which is of course a highly desirable feature and which overcomes this serious defect in the art. Another important feature of this device is that it presents no rough exterior surface, which means that when the rifle is used in the hunting fields there can be no danger of it becoming entangled in foliage, brush, or the like. Also, the mount will permit the "scope" to be positioned low on the rifle yet high enough to enable it to be used with bolt action rifles, and this of course is most desirable.

By the addition of another block on the receiver ridge, it is possible to employ the hunting

"scope" on a target rifle. Additionally, my novel mount in effect affords the accuracy of a target rifle in a hunting rifle.

While I have shown and described the preferred embodiment of my invention, I wish it to be understood that I do not confine myself to the precise details of construction herein set forth by way of illustration, as it is apparent that many changes and variations may be made therein, by those skilled in the art, without departing from the spirit of the invention or exceeding the scope of the appended claims.

I claim:

1. In a device for mounting a telescope on a rifle having a receiver, a block on the rifle forwardly of the receiver, a second block on the rifle rearwardly of the receiver, a base removably secured to the forward block and provided with an arcuate tongue, a clamp for the forward end of the telescope mounted on the base for pivotal movement about a vertical axis located by said arcuate tongue, an arcuate groove in the clamp slidably engaging the arcuate tongue, a second base removably secured to the rear block and having an arcuate tongue that is concentric with the vertical axis of the front clamp on its base, a clamp for the rear end of the telescope having an arcuate groove that slidably engages the arcuate tongue, depending lugs supported by the clamp, a windage adjustment comprising a cut-away portion in said second base, windage adjustment screws in the last mentioned base and projecting from opposite directions into said cut-away portion, the lugs of the rear clamp being disposed in the cutaway portion and engaged by said adjustment screws whereby adjustment of the telescope about the pivot point may be effected, and a locking device for each of said front and rear bases including a sliding block in each base and means for displacing the sliding blocks into releasable engagement with the blocks on which the bases are mounted whereby each base and its associated clamp may be removed from the rifle.

2. A mount for a telescope for attachment to a rifle provided with a receiver comprising a block

carried by the rifle forward of the receiver, a second block carried by the rifle rearward of the receiver, a base removably secured to the forward block and provided with a tongue having concentric arcuate end walls, a clamp for the forward end of the telescope pivoted to the base for movement about the vertical axis, a groove having an arcuate undercut face and an arcuate vertical face in said clamp and being concentric with and slidably fitting the arcuate end walls of the tongue, a gib having an undercut face and a vertical face positioned in an opening communicating with the groove so that its undercut face is in a position to engage the tongue and the vertical face is contiguous with the vertical face of the groove, means extending through the base to move said gib to effect a tighter fit between the clamp and the base, a second base removably secured to the rear block and having a tongue provided with arcuate end walls concentric with the pivot point of the front clamp to the front base, one of said end walls being angular and the other being vertical, a clamp for the rear end of the telescope provided with an arcuate groove that is concentric with the end walls of the second tongue, a second gib having a vertical face and an angular face positioned in the groove so that its vertical face is adjacent the vertical face of the tongue and its angular face is adjacent the face of the groove, means extending through the base to move the gib to provide a closer fit between the clamp and the base, a lug carried by the clamp, a windage adjustment comprising a cutaway portion in the base, windage adjustment screws in the base and projecting from opposite directions into said cutaway portion, the lug of the clamp being disposed in the cutaway portion and engaged by said adjustment screws whereby the clamp may be moved about the pivot point of the clamp to effect a windage adjustment, and a locking device carried by each base whereby each base may be removably secured to its block so that the telescope can be removed from the block without affecting the windage adjustment.

ERNEST L. MEISEL.
